[57] CLAIM

The ornamental design for a tote tray, as shown and described.

DESCRIPTION

FIG. 1 is a top perspective view of a tote tray showing my new design;

FIG. 2 is an end elevational view;

FIG. 3 is an elevational view showing the end opposite that seen in FIG. 2;

FIG. 4 is a side elevational view, the opposite side being a mirror image of the side shown;

FIG. 5 is a top plan view; and

FIG. 6 is a bottom plan view thereof.

FIG. 1

FIG. 3

FIG. 2

FIG. 4
